DIGITAL WRIST WATCH

Eugene Joseph Selek, Richardson, Tex., assignor to
Texas Instruments Incorporated

Filed Aug. 29, 1974, Ser. No. 501,948

Term of patent 14 years

Int. Cl. D10—02

U.S. Cl. D10—38

Fig. 2

Fig. 1

Fig. 3

Fig. 5

Fig. 4

FIG. 1 is a top right perspective view of a digital wrist watch showing an embodiment of my new design with time display activated;

FIG. 2 is a top plan view thereof;

FIG. 3 is a top end elevational view thereof;

FIG. 4 is a right side elevational view thereof, the left side being a mirror image thereof;

FIG. 5 is a bottom plan view thereof;

FIG. 6 is a top right perspective view of another embodiment of my new design of FIG. 1 with time display activated;

FIG. 7 is a top plan view thereof; and

FIG. 8 is a left side elevational view thereof; the ends and bottom are identical to FIGS. 3 and 5.

I claim:

The ornamental design for a digital wrist watch, substantially as shown and described.
